UNITED STATES PATENT OFFICE.

JOHN HOWARD FOOTE AND CHARLES W. RUBY, OF BROOKLYN, NEW YORK;
SAID RUBY ASSIGNOR TO SAID FOOTE.

MUSICAL INSTRUMENT.

SPECIFICATION forming part of Letters Patent No. 463,034, dated November 10, 1891.

Application filed May 20, 1889. Serial No. 311,399. (No model.)

To all whom it may concern:

Be it known that we, JOHN HOWARD FOOTE and CHARLES W. RUBY, both of Brooklyn, in the county of Kings, and in the State of New York, have invented certain new and useful Improvements in Musical Instruments; and we do hereby declare that the following is a full, clear, and exact description thereof, reference being had to the accompanying drawings, in 10 which—

Figure 1 is a perspective view from the front of a mouth-harmonica provided with reed covers of our improved construction. Fig. 2 is a like view of the same from the rear. 15 Figs. 3 and 4 are sections upon lines *x x* and *z z*, respectively, of Fig. 2; and Figs. 5 and 6 are perspective views from the outer and inner sides, respectively, of one of said covers detached.

20 Letters of like name and kind refer to like parts in each of the figures.

The design of our invention is to provide for the exposed parts of musical instruments a covering which shall be strong, durable, inexpensive, of little weight, and water-proof, and at the same time capable of any desired degree of ornamentation; and to this end our 25 said invention consists in a cover or covers for the parts of musical instruments, constructed from celluloid and adapted for use substantially as and for the purpose herein-after specified.

In the illustration of our invention it will be sufficient to show its use in connection 30 with one instrument, which, for convenience, is a mouth-harmonica A, of usual construction, upon each or either side of which is placed a cover B for the reeds, which cover is constructed from celluloid and is adapted to 35 fit down upon said side around said reeds, and immediately over the latter has an out-

ward swell, so as to leave the tongues free to vibrate. The raised portion of said cover has, preferably, an outward and rearward inclination or curved form from its front edge 45 nearly to its rear edge, and from thence to said edge has a sharp rearward and inward slope, near the lower end of which latter is provided a row of air-openings *b* and *b*.

At each end of the cover B is provided a 50 flat part *b'*, through which, through the end of the harmonica A, and through the corresponding part *b'* of the opposite cover B passes a bolt C, which operates to bind said parts together; or said covers may be attached 55 with pins, if desired. Other air-openings *b*² may be provided, if desired, within the main portion of the raised part of said cover.

The covers B and B may have any desired 60 color or shade, and, if colored, may be mottled or plain, as the material of which they are composed is capable of a great variety of color ornamentation at a trifling increase in expense. They are unaffected by moisture or any ordinary degree of temperature, are 65 very light, strong, and durable, and afford a better protection to the reeds than do the ordinary metal covers.

Having thus described our invention, what we claim is—

70 A mouth-harmonica having reed covers or shields made of celluloid, substantially as and for the purpose specified.

In testimony that we claim the foregoing, we have hereunto set our hands this 13th day 75 of May, 1889.

JOHN HOWARD FOOTE.
CHARLES W. RUBY.
